UNITED STATES PATENT OFFICE

2,583,471

CONVEYER DRIVE

Leslie Alfred Collis, Radlett, England, assignor to
 J. Collis & Sons Limited, London, England, a
 British company

Application December 15, 1948, Serial No. 65,372
 In Great Britain December 19, 1947

4 Claims. (Cl. 198—203)

1

This invention relates to conveyors, more particularly belt, slat and chain conveyors (hereinafter referred to generically as "belt conveyors"). Belt conveyors are made up of a number of conveyor units each comprising a frame within which the conveyor belt is mounted in the usual way on, at least, end rollers, the spindles of which run in bearings on the outside of the frame, the bearings at the ends of two consecutive units being coupled together by means of a removable self-contained coupling unit engaging therewith, as disclosed in copending United States application Serial Number 741,490, filed April 15, 1947, and issued August 7, 1951, as Patent No. 2,563,427. Now it will be appreciated that the satisfactory installation and operation of such a conveyor is dependent upon the correct location of the spindles of juxtaposed units in order that they may be coupled together by the self-contained coupling unit. A comparatively high standard of precision manufacture is called for and any substantial misalignment of the units of the conveyor prevents its installation and operation. One object of the present invention is to overcome these possible disadvantages of the construction of conveyor described in the said copending patent application while still retaining the advantages of the unit system. A further object of the present invention is to improve the inter-frictional contact between the driving rollers and the conveyor belts in such conveyors.

The belt conveyor according to the present invention is of the kind comprising a plurality of conveyor units each comprising a frame within which the belt is mounted on, at least, end rollers, the juxtaposed ends of the units being carried by stands, slings or like supports and is characterised by the provision on the said stands or like supports of at least one friction driving roller adapted, in conjunction with the end roller of one unit, to nip the belt of the said unit, means being provided for driving said friction roller to cause the same to drive said belt.

Preferably the friction roller is adapted to engage with the belts of the units as they pass over the juxtaposed end rollers in order to transmit the drive from one unit of the conveyor to the next.

Conveniently the ends of the conveyor units are carried in cradles on the stands or like supports, said cradles being so constructed as to allow vertical movement of the ends of the conveyor units whereby the weight of the conveyor units and the weight of the articles being conveyed thereby will be transmitted to the frictional driving roller or rollers to increase the frictional contact.

Alternatively, the cradles on the stands or like supports may be so constructed as to prevent vertical movement of the ends of the conveyor units once they are in position and means, for example, such as tensioning screws or springs,

2

may be provided for increasing and maintaining the pressure between the driving roller or rollers and the conveyor belts.

In order that this invention may be the more clearly understood and readily carried into effect reference may be made to the accompanying drawings in which:

Figure 1 is a somewhat diagrammatic end elevation of a stand supporting the juxtaposed ends of two conveyor units and having a single frictional driving roller for transmitting the drive from one conveyor unit to the next,

Figure 2 is a view similar to Figure 1 showing a modified form of the present invention,

Figure 3 is a view similar to Figure 1 but showing an embodiment in which the ends of the conveyor units are held against vertical movement on the stand.

In the accompanying drawings, for the sake of clarity, no details of the construction of the conveyor units have been shown as these form no essential part of the present invention. One very convenient construction of conveyor is described in the co-pending patent application above referred to and reference may be made to the specification thereof for details of construction.

Referring now to the accompanying drawings the units of the conveyor indicated generally as A and B are substantially the same as the unpowered units described in the co-pending patent application above referred to, with the exception that the ends of the spindles 10 of the end rollers 11 of the units need not project beyond the bearings 12. The cradles 13 on the stands, slings or other supports 14 are so constructed that the bearings 12 on the ends of the units may move up and down somewhat without leaving the cradles. Rotatably mounted on the top of the stand or the like 14 and between the two parts of the cradle is a friction driving roller 15. The spacing between the two parts of the cradle 13 and the diameter of the driving roller 15 is such that when the bearings at the ends of the units are placed in the cradle the conveyor belt 16 contacts with the face of the driving roller before the bearings reach the bottom of the cradle. The weight of the conveyor units A and B and the weight of the packages or other articles being conveyed thereby will press the conveyor belt into good frictional contact with the driving roller and so the drive will be transmitted from one unit to the next and so on along the conveyor line. The drive from the power unit is preferably applied to one or more of the frictional driving rollers 15 of the complete conveyor. For example, one or more of the frictional driving rollers 15 may be arranged on the top of a driving cabinet and be driven from a power unit in said cabinet, the frictional driving roller on the cabinet being the power output from the cabinet and the end rollers of the units with which it is in contact

the power input roller. It will be appreciated that with such a method of transmitting the drive from one unit to the next it is no longer a matter of precision engineering to produce the cradles since a slight variation of the spacing will easily be taken up on the driving roller. Furthermore, the conveyor units may be freely removed from and replaced in the cradles as and when desired.

In a modified form of the present invention illustrated in Figure 2, the top of the stand or the like 14 is provided with three spaced friction rollers 17, 18 and 19 freely rotatable on parallel axes, the spacing of the rollers being such that the end rollers 11 of the units A and B may be laid between the outer and inner rollers with the conveyor belt in engagement with two of the rollers as shown. In this construction, again, the weight of the conveyor units and the weight of the packages or other articles being conveyed thereby will keep the conveyor belt in good frictional driving contact with the surfaces of the rollers and the drive will be transmitted from one unit to the next as before. The spacing of the rollers 17, 18 and 19 and their diameters relative to the diameter of the end rollers 11 of the conveyor units is preferably such that the outer rollers 17 and 19 serve as snubbing and nipping rollers to press the conveyor belt into engagement with the end roller and such that the resultant forces between the parts tend to keep the rollers together.

The roller 18 corresponds to the roller 15 of the construction shown in Figure 1 and functions in the same way.

In the embodiment shown in Figure 2 the cradles 13 may, if desired, be omitted since the end rollers of the adjoining conveyor units will be positioned adequately by means of their engagement with the central and outer rollers. The conveyor units are quite free and need only be held against lateral movement on the rollers 17, 18 and 19.

In a further embodiment of the present invention, which is illustrated in Figure 3 of the accompanying drawings, the cradles 20 at the top of the stand or support 14 instead of opening out to the top as in the constructions illustrated in Figures 1 and 2 open out to the sides and the conveyor units A and B are slipped into the same end on.

Pivoted clips 21 are provided on the cradles, the said clips being engaged by the bearings as the conveyor units are inserted into the cradles and swung round so that once the conveyor units are in position they are held against lengthwise movement by reason of the arm of the clip 21 which closes the open end of the cradle. A latch 21a may be provided for holding the clip closed. The open and closed positions of the clip 21 are shown respectively on the left hand side and right hand side of Figure 3. It will be seen that once the conveyor units are in place, and the clips closed, the end rollers of the conveyor units are held against movement both vertically and horizontally. A friction driving roller 22 is mounted freely rotatable in the stand or the like between the two cradles as in the embodiments shown in Figures 1 and 2, this roller contacting the conveyor belts to transmit the drive from one unit to the next. In this construction, however, the spindle of the driving roller 22 is vertically adjustable, say by means of a tension screw 23, so that the pressure between the driving roller 22 and the conveyor belts 16 may be adjusted to

transmit the required drive. If desired, tension springs may be provided in place of the tension screw 23.

In all the embodiments of the present invention hereinbefore described the friction rollers have been employed to transmit the drive from one unit to the next. This is not, however, essential since, if desired, the friction roller may be driven from a suitable power source and serve to drive one belt only. Similarly, each of the juxtaposed ends of adjoining conveyor units may be provided with its own individual friction roller which is driven from a suitable power source and serves to drive its own individual unit.

Although the main object of the present invention is to dispense with the use of a self-contained coupling unit such as that described in the above identified application between the conveyor units such a coupling unit may, if desired, be used additionally to the above described means to increase the inter-unit driving capacity.

I claim:

1. A support for adjoining ends of belt conveyor units, each unit comprising an end roller with the belt passing over said roller, said support having juxtaposed cradles receiving the end roller of said conveyor unit, said support having a friction driving roller thereon arranged to frictionally engage the belt of each said conveyor unit to drive same, each conveyor unit being movable vertically in said cradles, whereby the weight of each unit and the articles carried thereby will be transmitted to the frictional driving roller to increase the frictional contact between said belts and driving roller.

2. A support for adjoining ends of belt conveyor units, each unit comprising an end roller with the belt passing over said roller, said support having juxtaposed cradles receiving the end roller of each conveyor unit, said support having a friction driving roller thereon arranged to frictionally engage the belt of each conveyor unit to drive same, each cradle being open to the side of said support so that each conveyor unit may be inserted endwise thereinto, means for supporting said conveyor units against lengthwise movement in said cradles and means for ensuring a driving contact between the friction driving roller and the belt.

3. A support according to claim 2, including tension means for maintaining the frictional driving roller in contact with the belts.

4. A belt conveyor according to claim 3, including a pivoted clip which is automatically moved to close the openings of the cradles as the conveyor units are inserted into said cradles.

LESLIE ALFRED COLLIS.
